UNITED STATES PATENT OFFICE.

PAUL C. HILL, OF CEMENT, OKLAHOMA.

ROTARY CORE DRILL FOR OIL WELLS.

1,427,685.

Specification of Letters Patent. Patented Aug. 29, 1922.

Application filed December 9, 1921. Serial No. 521,128.

To all whom it may concern:

Be it known that I, PAUL CORTLANDT HILL, a citizen of the United States, residing at Cement, in the county of Caddo and State 5 of Oklahoma, have invented certain new and useful Improvements in Rotary Core Drills for Oil Wells, of which the following is a specification.

This invention appertains to certain improvements in well drills, and more particularly to a rotary core drilling type of the same involving a means for taking samples of the earth's stratum through which the drill may be working at any time during 10 15 the drilling operation.

The principal object of the invention is to provide for a well drill as characterized, and one wherein the sample taking means is operable throughout the working movement of the drill, but the cuttings taken up by the same are delivered therefrom to the interior of the drill and washed from the latter outwardly of the head of the drill until it is desired to make an examination 20 25 of the cuttings as may be contained within the means at a particular time, when the drill is to be withdrawn from the well bore, and the sample taking means extracted from the drill for the purpose.

Another object of the invention is to provide for a drill of the class mentioned, and one of an extremely simplified, inexpensive, durable and efficient construction and arrangement of parts, which parts are readily 30 35 assembled and detachable one from the other for purposes of replacement and repair.

A further object of the invention is to provide for a drill of the class mentioned, and one involving the use of a sampling tube disposed centrally of the drill proper, and which is made up of preferably detachable sections adapted for ready removal from operative position for examination of a contained sample, or for replacement and repair 40 45 50 of the parts thereof, the lower portion or section of the tube having its lower end projected below the lower end of the drill proper and provided with earth cutting elements or cutting teeth, whereby to aid in the freeing of the cuttings taken up by the same for sampling purposes.

With the foregoing and other objects in view, the invention resides in the certain novel and useful construction, arrangement 55 and operation of parts as will be hereinafter more fully described, set forth in the ap-

pended claim, and illustrated in the accompanying drawing, in which:—

Figure 1 is an elevation, partly in section, of a preferred embodiment of the drill, 60

Figure 2 is a vertical section of the drill, and

Figure 3 is an enlarged fragmentary sectional detail of the upper end portion of the sampling tube of the drill. 65

Referring to the drawing, the numeral 10 indicates a drill head or bit portion, preferably of the usual and so called "fish tail" type having a tapered threaded shank or portion 11 rising centrally from the upper end edge 70 thereof for threaded engagement with the correspondingly tapered and threaded lower end portion of the bore 12 of a coupling member or sleeve 13, the upper straight portion of the bore of the latter being threaded 75 for engagement on the lower complementally threaded end of a hollow drill stem 14. The upper edge portion of the drill head or bit 10 is thickened equally with respect to the opposite side faces of the blade portion 80 thereof, as at 15, while the latter is thickened equally at the opposite sides of the same and on its vertical center as at 16, the thickened portions 15 being formed to curve 85 downwardly as at 15' into the said opposite faces of the blade portion, and the thickened portion 16 to taper downwardly from its upper end substantially as is shown in Figure 2. Extending upwardly of the opposite side portions of the thickened portion 90 95 15 are a pair of ducts 17 and 18, the lower ends of which open through the curved walls thereof, while the upper ends of the same open through the end face of the tapered shank 11 and communicate with the bore 12 of the coupling 13 for the purpose of discharging water to either side of the blade portion of the drill head or bit to aid the latter in its drilling operation.

Extending vertically and centrally of the 100 thickened portion 16 of the drill head or bit 10, is a bore 19 which has inserted in its lower end a sample taking tube section 20, and in its upper end a sample taking and receiving section 21, the lower section 20 having its upper end threaded as at 20' into engagement with the wall of the bore 19 at a point removed at a substantial distance from the upper end thereof, and its lower end projecting for a relatively short distance below 105 the lower edge of the drill head or bit, while the connected end of the upper portion 21

is threaded as at 21' into the upper end of the bore 19 and into abutting relation with respect to the upper end of the lower section 20. The upper section 21 of the sample taking device projects concentrically upward of the aligned bores of the coupling 13 and the drill stem 14 for a suitable distance, and has its upper open end threaded as at 21" to receive thereon an annular cap face or member 22, on which is pivoted or hinged as at 23 a closure member 24, the under face of the latter having an annular groove within the same for the reception of a gasket 25 arranged to seat on the open end of the upper tube section 21. The lower projecting end of the lower tube section 20 has its edge formed to provide a series of cutting elements or teeth 26, whereby to assure of the breaking up of the cuttings of the drill proper to a suitable degree of fineness so as to freely pass upwardly of the sampling tube sections 20 and 21, and by unthreading the lower section 20, the cutting teeth 26 may be readily sharpened without the taking apart of the drill as a whole, or this sharpening operation may be readily accomplished without removing the lower section 20 from its position within the drill head or bit bore.

In the use of the drill, a well bore is started with the same, and water may be discharged downwardly of the stem 14 to aid in the earth cutting operation. As the drill progresses downwardly through the earth, the cuttings of the drill proper are further broken up by the cutting teeth 26 of the lower sampling tube section 20, and the fine cuttings passed upwardly of the latter and into and through the upper section 21 and are discharged outwardly of the upper end of the section 21, the closure 24 being forced to open position by the pressure exerted thereon by the cuttings, the passageway through the sections 20 and 21 being kept free from clogging by the presence of water in the well bore and of the upflow of a certain amount of the same therethrough, the pressure of the downflow of water in the drill stem 14 and the force of gravity normally forcing the closure on the upper end of the section 21 and closing the passage through the same. When it is not desired to test out samples of the earth passing upwardly of the tube sections 20 and 21, the cuttings are discharged from the upper end of the upper section 21 and into the bore of the drill stem, from whence it is washed outwardly of the ducts 17 and 18 by the water flowing therethrough. However, when it is desired to test or examine a sample of the earth, the drilling operation is stopped, and the drill head or bit 10 and the stem 14 are withdrawn from the well bore, when the upper tube section 21, or both this section and the lower section 20, are unthreaded and removed from the drill head or bit 10, and the cuttings therein removed for such purpose. This removal of the upper section 21 for the purpose of testing or sampling the cuttings therein may be accomplished without removing the drill from the well bore, if desired, and this is to be readily and quickly accomplished by the lowering of a suitable grappling tool (not shown) downwardly of the drill stem, and into engagement with the exposed length of the section 21, whereby the same may be unthreaded from operative position and withdrawn upwardly of the drill stem, when, after the retained sample cuttings therein have been removed, the section 21 may be lowered within the stem and rethreaded into operative position.

From the foregoing, it will be readily apparent that, while a preferred embodiment of the drill has been described and illustrated herein in specific terms and details of construction, arrangement and operation, various changes in and modifications of the same may be resorted to without departing from the spirit of the invention, or the scope of the claim appended hereto.

Having thus fully described the invention, what is claimed, is:—

In a well drill as characterized, a hollow drill stem, a drill bit carried at the lower end of said stem, a straight sectional tubular sample taking device mounted vertically of said drill bit, the lower of the sections of said device being removably secured in said drill bit and having its lower end projecting for a distance below the lower end edge thereof and the upper of the sections being removably secured in said drill bit and extending upwardly from the same within said drill stem and in alignment with the said lower section, and a hinged closure at the free end of the upper of the sections of said device.

In testimony whereof, I affix my signature hereto.

PAUL C. HILL.
